PLANSIFTERS

Paul Eppenberger, Amriswil, Switzerland, assignor to
Gebrueder Buehler, Uzwil, Switzerland, a Swiss firm
Filed Oct. 14, 1959, Ser. No. 846,498
Claims priority, application Switzerland Sept. 16, 1959
18 Claims. (Cl. 209—319)

The present invention relates to improvements in plansifters, and more particularly to the construction, arrangement and sealing of sifter units in plansifter compartments.

This application is a continuation-in-part of my application Serial No. 697,572, filed on November 20, 1957, now abandoned.

An important object of the invention is to provide a plansifter whose sifter units, i.e. its collecting bottoms and sifter frames, may be readily and easily inserted, withdrawn and cleaned.

Another important object of the invention is to provide a plansifter embodying a sanitary, simple and reliable sealing arrangement for the sifter frames and collecting bottoms along the surfaces of their abutment with each other and with the supporting structure therefor, whereby the processed goods are prevented from settling in any zone of the plansifter during the sifting operation.

A further object of the invention is to provide a plansifter of the above outlined characteristics whose sifter units are constructed with a view to facilitate their insertion into or their withdrawal from the plansifter compartment.

Still another object of the invention is to provide an improved collecting bottom for use in the plansifter embodying the above outlined advantages.

With the above objects in view, the invention resides essentially in the provision of a plansifter which comprises a housing defining one or more compartments for a number of vertically spaced flanged supporting elements which are arranged in aligned pairs in the interior of the housing, and at least one pair of sifter units including a collecting bottom member and a sifter frame member one of which is supported by the flanges of an aligned pair of supporting elements and the other of which is located above and is slidable with respect to the first mentioned member.

Sealing means may be provided between one of the sifter units and the flanges of respective supporting elements, and additional sealing means may be placed between two adjacent sifter units.

Another feature of the invention resides in the provision of resilient means, e.g. leaf or wire springs, which are adapted to press the sifter units against the flanges of supporting elements to enhance the action of sealing means. The resilient means may be disposed between the sifter units supported by the same pair of supporting elements or between a sifter unit and the flanges of the supporting elements thereabove. Such resilient means may be connected directly to the sifter units or to the flanges of the supporting elements therefor. Alternately, one of the sifter units may be formed with upwardly projecting extensions which engage with the flanges of the supporting elements thereabove and compress the yieldable sealing means sufficiently to prevent accumulation of processed goods between the sifter units and/or between a sifter unit and the supporting elements therefor. The advantage of such construction is in that it operates without metallic resilient elements.

An additional feature of the invention resides in the provision of specially arranged battens on selected sifter units which facilitate guiding, sealing and retention of respective units in the plansifter housing without adding to the overall height of the plansifter.

2

The invention will be described in greater detail with reference to the accompanying drawings in which:

FIG. 1 is vertical section through one compartment of a plansifter embodying the invention, the section being taken on the line I—I of FIG. 2, as seen in the direction of arrows;

FIG. 2 is a vertical section through the plansifter compartment taken along the line II—II and at right angles to the section of FIG. 1, as seen in the direction of arrows;

FIG. 3 is an enlarged detail sectional view taken on the line III—III of FIG. 1, as seen in the direction of arrows;

FIG. 4 is a fragmentary section drawn to a slightly reduced scale and taken along the line IV—IV of FIG. 3, as seen in the direction of arrows;

FIG. 5 illustrates a modification of the construction shown in FIG. 3;

FIG. 6 is a detail view of the modified structure as seen in the direction of arrows from the line VI—VI in FIG. 5;

FIG. 7 is a detail view similar to that of FIG. 6, showing a different mounting of the resilient means;

FIG. 8 illustrates a further modification in a view similar to that of FIGS. 3 and 5, showing a sealing arrangement which operates without metallic resilient means;

FIG. 9 is a vertical section taken along the line IX—IX of FIG. 8, as seen in the direction of arrows; and

FIG. 10 is top plan view of a collecting bottom utilized in the modified plansifter of FIGS. 8 and 9.

Referring now in greater detail to the illustrated embodiments, and first to that shown in FIGS. 1 to 4, the plansifter comprises a housing 1 provided with partitions 2 which define compartments 3. The partitions support horizontally aligned pairs of supporting elements here shown as U-shaped channels 5 each of which is formed with a pair of vertically spaced substantially horizontal flanges 6, 7, respectively. The lower flanges 7 of each aligned pair of channels 5 slidably support sifter units or frames 9 while the upper flanges 6 slidably support sifter units in the form of collecting bottoms 10. As is known, the purpose of the members 10 is to collect the fractions passing through the sifter frames thereabove.

A bolting cloth 13 and a wide-mesh wire cloth 14 are stretched across the upper and lower sides, respectively, of each sifter frame 9. Cloth 14 supports means (not shown) for cleaning the cloth 13, such as pieces of belting, balls or the like. Alternately, the cloth 13 may be cleaned by means of conventional brushes, if desired.

The product fractions to be assorted and classified enter the plansifter through the tubular intake member 30. The fractions passing along and beyond the collecting bottoms 10 are carried away laterally through the ducts 31 in the direction of arrows 48 until deflected by the members 32 onto the sifter frames 9 and collecting bottoms 10 therebelow. Terminal boxes 33, 34 constitute lateral walls of the plansifter compartment 3. Each terminal box comprises bypass ducts 35, 36 for detouring and discharging the overriding and rejected fractions, respectively. The rejected fractions of the material processed in the plansifter are discharged through tubular outlets 37. The ducts 35, 36 extend the full width of the sifter frames 9, and are separated from each other by U-shaped walls 38. Certain novel features of the terminal boxes 33, 34 are disclosed and claimed in my United States Patent No. 2,901,109 for "Plansifter Compartment," granted on August 25, 1959.

Each collecting bottom 10 comprises a pair of border battens 21 which are adjacent to its longer sides and which extend from one, e.g. the lower, of its major surfaces. A pair of cross battens 22 is adjacent to the opposing, e.g. upper, major surface and extends along the shorter sides of each member 10. Such arrangement of battens

21, 22 permits full utilization of the height of the plansifter since the inflow may occur through the entire space between a bolting cloth 13 and the collecting bottom 10 thereabove. As may be observed in FIG. 3, the vertical spacing between a bolting cloth 13 and the collecting bottom 10 thereabove corresponds to the height of battens 21. The same consideration holds true for the outflow of treated material.

An important function of the battens 22 is in that their outer surfaces constitute seals against the adjacent terminal boxes 33, 34. As is known, the collecting bottoms 10 must be mounted at a certain distance from the sifter frames 9 so that the material passing through the cloth 13 and wire screen 14 may flow along the collecting bottoms in the direction toward the lateral ducts 31. Thus, the cross battens 22 simultaneously form seals against the terminal boxes, i.e. there is no increase in the height of a so-constructed plansifter since the space of a width corresponding to the height of the battens 22 is necessary for proper operation of the device.

The outer sides of the battens 21 are formed with elongated recesses 21r for the reception of respective flanges 6. Such arrangement prevents a collecting bottom 10 from dropping onto the lower flanges 7 of the respective supporting elements or channels 5 when the sifter frame 9 therebelow is removed.

As is shown in FIG. 4, each batten 21 carries two pairs of retaining pins 25 which support two spaced resilient members in the form of wire springs 24. These springs bear against and are slidable along the sifter frame 9 therebelow when one of the sifter units 9, 10 is moved with respect to the other unit, i.e. when either the collecting bottom 10 or the sifter frame 9 therebelow is inserted into or removed from the plansifter compartment 3. In addition, these springs cause the members 10, 9 to bear against the upper and lower flanges 6, 7, respectively, of an aligned pair of supporting elements or channels 5. Thus, the mounting of resilient means 24 is such that they urge a collecting bottom in a direction away from the sifter frame 9 therebelow.

Sealing strips of suitable yieldable elastic material, indicated by reference numerals 26, are provided between the sifter frames 9 and the respective flanges 7. These strips extend into and are retained in elongated recesses 9a formed in the undersides of the sifter frames 9. Recesses 9a are parallel with the lower flanges 7 of supporting elements 5. The sealing action of the strips 26 is enhanced by the resilient means 24 which constantly urge the sifter frames 9 toward their respective flanges 7.

In the absence of a collecting bottom (see, for example, the top of FIG. 3), special battens 27 are provided for bracing the uppermost sifter frame 9, i.e. for urging the uppermost sifter frame against the flanges 7 forming part of the uppermost pair of supporting elements or channels 5. The battens 27 are slidable beneath the uppermost pair of flanges 6 and carry resilient means preferably identical with the springs 24 which bear against the upper side of the adjacent sifter frame 9.

FIG. 5 illustrates a modification of the system shown in FIGS. 1 to 4 whose purpose is to prevent entry of product fractions between the battens 21 of the collecting bottoms 10 and the sifter frames 9 therebelow. As mentioned hereinbefore, the resilient means 24 urge the battens 21 in a direction upwardly and away from the sifter frames 9 therebelow; thus, a slot X (shown greatly exaggerated in FIG. 4) develops between the sifter unit 9 and the battens 21. This slot is rapidly filled with comminuted goods, which is highly undesirable. To prevent the formation of such slots, a second sealing strip 40 is provided between each batten 21 and the sifter frame 9 therebelow. The modified construction of FIG. 5 utilizes L-shaped supporting elements 41 whose horizontal flanges 42 abut against the undersides of the sifter frames 9 with the sealing strips 26 therebetween. Adjacent to

the sealing strip 40, each batten 21 is formed with a downwardly projecting elongated rib 21b which extends into a recess 9b formed in the sifter frame 9 therebelow. The depth of each recess 9b preferably exceeds the height of the respective rib 21b, which enables the resilient means 43 to compress the yieldable sealing strip 40 when the collecting bottom is inserted into the plansifter compartment. Each of resilient means 43 preferably assumes the shape of a semielliptical leaf spring one end of which is free to slide along the collecting bottom when the spring is compressed by the flange 42 thereabove. Such construction of the leaf springs facilitates the insertion of collecting bottoms into the plansifter compartment. Resilient means 43 are mounted on the upper sides of the battens 21 forming part of collecting bottoms 10, and bear against the undersides of the flanges 42 thereabove. Thus, instead of urging a collecting bottom 10 away from the sifter frame 9 therebelow, the springs 43 urge the collecting bottoms 10 in downward direction to enhance the sealing action of strips 26 and 40. Such construction brings about the important advantage that the sealing strips prevent escape of processed goods laterally between the undersides of battens 21 and the upper sides of the sifter frames 9 into contact with the supporting elements 41, i.e. the sealing means are closer to the path of the conveyed material. The sealing strips 26, 40 may consist of felt, plush, or any other suitable resiliently-yieldable material.

The uppermost sifter frame 9 shown in FIG. 5 operates with a retaining and spacing frame member consisting of battens 21a, 22a, the former of which also carries a leaf spring 43 bearing against the flange 42 of the supporting element 41 thereabove. The retaining and spacing frame member consisting of battens 21a, 22a replaces a collecting bottom 10 and permits unimpeded descent of processed goods directly onto the sifter frame 9 therebelow. In addition, the retaining frame member holds the uppermost sifter frame in requisite position during the sifting operation, i.e. this special frame member also performs the function of the battens 27 shown in FIG. 3.

As is shown in FIG. 7, the resilient means 43 may be attached to the undersides of the flanges 42 to bear against the upper sides of the battens 21.

Each collecting bottom 10 may be formed with at least one substantially convex protuberance 44 which constitutes a handgrip means and facilitates the withdrawal of the collecting bottom from the plansifter compartment. It can be observed in FIG. 6 that the space between a cross batten 22 and the sifter frame 9 thereabove is rather narrow, i.e. it is insufficient to permit insertion of the fingers which could grip the batten 22 to withdraw the collecting bottom 10 from the plansifter compartment. By providing the aforementioned bulges or protuberances 44, the operator can insert his fingers into the concave recesses or cavities formed at the undersides of the collecting bottoms to withdraw the latter against the force of the resilient means 43. Upon withdrawal of the collecting bottom, the operator has no difficulty in removing the sifter frame 9 which is then freely slidable along the flanges 42 of the corresponding supporting elements 41. Alternately, the protuberance 44 may be replaced by another handgrip means, for example, by a pin or a handle located below the batten 22. The provision of handgrip means in the form of protuberances has the advantage that the protuberances do not restrict the inlet openings to the sieves therebelow.

FIGS. 8 to 10 illustrate a modification of the assembly shown in FIGS. 5 and 6. The battens 21, 21a comprise upwardly projecting extensions 45 which replace the resilient means 43. Each extension is formed with two inclined surfaces 46 which facilitate the insertion of the collecting bottom, and each extension is preferably coated with a yieldable sealing material 47, e.g. a layer of plush, felt or the like. The extensions 45 bear against the un-

dersides of the respective flanges 42 and thus compress the sealing strips 26 and 40 by urging the latter against the upper sides of the sifter frames 9 and against the upper sides of the flanges 42, respectively. Thus, the arrangement of FIGS. 8 and 9 operates without metallic springs as it merely utilizes the resiliency of yieldable sealing strips or layers 26, 40 and 47 for holding the sifter frames 9 and collecting bottoms 10 in required operative position. FIG. 10 illustrates that an extension 45 is provided at each of the four corners of a rectangular collecting bottom 10.

A simplified version of the construction shown in FIGS. 8 and 9 utilizes only the sealing strips 40, i.e. the sealing strips 26 and 47 may be omitted, as long as the height of projections or extensions 45 is selected in such a way that these extensions cause sufficient compression of sealing strips 40 when the collecting bottoms 10 are inserted into the plansifter housing.

The operation of the assemblies shown in FIGS. 5-6 and 8-9 is as follows:

The sifter frames 9 are held against movements with respect to the adjacent flanges 42 by the collecting bottoms 10 and by the spacer frame members 21a, 22a thereabove. The sealing strips 40 prevent entry of conveyed material into the spaces between the sifter frames 9 and the battens 21 or 21a thereabove; thus the goods travelling laterally along the screens 13 of sifter frames 9 can find no crevices or slots and cannot remain in the plansifter.

The goods passing along the upper sides of collecting bottoms 10 advance into the ducts 31 (see the arrows 43). The goods which cannot pass the bolting cloths 13 are discharged in the direction of arrows 49 and descend in the ducts 35 or 36 onto selected sifter frames therebelow (see FIG. 1). As mentioned hereinbefore, the frame members consisting of battens 21a, 22a permit the descent of goods from the inlet duct 30 or from a higher sifter frame directly onto the next-lower sifter frame. The handgrip means 44 shown in FIGS. 5 and 6 need not be provided on the spacer frame members because the transverse battens 22a are readily accessible and may be grasped by an operator's hand to permit convenient withdrawal of such spacer frame members from the plansifter compartment. Once the collecting bottoms 10 or the spacer frame members are removed, the retaining action upon the sifter frames is terminated and the latter then offer no resistance during their withdrawal from the plansifter.

I wish it to be understood that I intend to include as within the scope of my present invention all such modifications as may be necessary to adapt the plansifter to varying conditions and uses and which fall within the terms or spirit of the appended claims.

I claim:

1. In a plansifter, in combination: a housing; vertically spaced pairs of parallel supporting elements in said housing, each supporting element having at least one flange; a sifter frame member and a collecting bottom member in said housing, one of said members being slidably supported by the flanges of one pair of said supporting elements and the other member being located above and slidable on said one member.

2. The structure as set forth in claim 1, wherein said one member has an underside and further comprising sealing means between said underside and the flanges of the respective supporting elements.

3. The structure as set forth in claim 1, further comprising sealing means between said sifter frame member and said collecting bottom member.

4. The structure as set forth in claim 1, further comprising resilient means located between said other member and the flanges of supporting elements thereabove for urging said other member in a direction toward said one member.

5. In a plansifter, in combination: a housing; vertically spaced pairs of parallel horizontal supporting channels in said housing, each channel having a first flange and a second flange vertically spaced from said first flange, a sifter frame member slidably supported by the first flanges of one pair of said channels; and a collecting bottom member having a first and a second pair of sides and a first and a second major surface, and comprising a first pair of battens each extending along one of the first pair of said sides at one of said major surfaces, and a second pair of battens each extending along one of the second pair of said sides at the other of said major surfaces in sliding contact with the second flanges of said one pair of channels.

10 6. In a plansifter, in combination: a housing; vertically spaced pairs of parallel horizontal supporting channels in said housing, each channel having an upper flange and a lower flange; a sifter frame member and a collecting bottom member slidably supported by a pair of said supporting channels; and spring elements operating between said members for urging one member against the upper flanges and the other member against the lower flanges of the respective pair of said channels.

15 7. The structure as set forth in claim 6, wherein the bottom member has a first and a second pair of sides and further comprising a first pair of battens each thereof extending along one of the first pair of said sides above the collecting bottom member, and a second pair of battens each thereof extending along one of the second pair of said sides below the collecting bottom member.

20 8. The structure as set forth in claim 6, further comprising a pair of sealing strips fixed to the sifter frame member and abutting against the flanges against which the sifter frame member is urged by said spring elements.

25 9. The structure as set forth in claim 6, wherein the sifter frame member is disposed below the collecting bottom member and is urged by said spring elements against the lower flanges of the respective pair of said channels.

30 10. The structure as set forth in claim 6, further comprising a pair of battens insertable into said housing as a replacement for said collecting bottom member, each batten being disposed above the sifter frame member and slidable along an upper flange of the respective pair of said channels, and spring elements operating between said battens and the sifter frame member for urging the latter against the lower flanges and for urging the battens against the upper flanges of the respective pair of said channels.

35 11. As a novel article of manufacture for use in a plansifter, a collecting bottom member having a first and a second pair of sides and two major surfaces; a first pair of battens each extending along one of the first pair of said sides adjacent to one of said surfaces; and a second pair of battens each extending along one of the second pair of said sides adjacent to the other of said surfaces.

40 12. In a plansifter, in combination: a housing; vertically spaced pairs of parallel supporting elements in said housing, each supporting element having a substantially horizontal flange; a sifter frame member and a collecting bottom member in said housing, one of said members being slidably supported by the flanges of one pair of said supporting elements and the other member being located above and slidable with respect to said one member;

45 sealing strips of resiliently yieldable material between said members, each strip extending in parallelism with one of said flanges; and means located between said other member and the flanges of the pair of supporting elements thereabove for urging said other member in a direction toward said one member and for compressing said sealing strips.

50 13. The structure as set forth in claim 12, wherein said sifter frame member is located below said collecting bottom member and has an underside formed with a pair of spaced parallel recesses adjacent to the respective

flanges, and further comprising a second sealing strip in each of said recesses, said second sealing strips being urged by said means against the flanges of the supporting elements therebelow when said members are inserted into the plansifter housing.

14. The structure as set forth in claim 12, wherein said collecting bottom member is located above said sifter frame member and comprises a pair of downwardly extending parallel battens, each batten having an underside and said sealing strips being fixed to the undersides of said battens.

15. The structure as set forth in claim 14, wherein each of said battens comprises a downwardly extending rib adjacent to the respective sealing strip, and said sifter frame member is formed with recesses for the reception of said ribs.

16. In a plansifter, in combination: a housing; vertically spaced pairs of parallel horizontal supporting elements in said housing, each supporting element having a substantially horizontal flange; a sifter frame member in said housing resting on the flanges of one pair of said supporting elements; a collecting bottom member above said sifter frame member, said collecting bottom member having a pair of parallel battens extending in paral-

lism with the flanges of said supporting elements and each batten comprising at least one upwardly projecting extension engaging with the flange of the supporting element thereabove for urging the sifter frame member against the flanges of the supporting elements therebelow; and a sealing strip of yieldable material inserted between each batten and the sifter frame member.

17. The structure as set forth in claim 16, wherein each of said extensions is formed with at least one inclined surface for facilitating the insertion of said collecting bottom member into the plansifter housing.

18. The structure as set forth in claim 16, wherein said collecting bottom member is of rectangular contour and an extension is provided at each of its four corners.

15
